Attorney.

UNITED STATES PATENT OFFICE.

STEPHEN J. CLULEE, OF ATTLEBORO, MASSACHUSETTS, ASSIGNOR TO BAY STATE OPTICAL COMPANY, A CORPORATION OF MAINE.

EYEGLASS-HOOK.

No. 895,074.

Specification of Letters Patent.

Patented Aug. 4, 1908.

Application filed January 23, 1908. Serial No. 412,239.

To all whom it may concern:

Be it known that I, STEPHEN J. CLULEE, a citizen of the United States, residing at Attleboro, in the county of Bristol and State of 5 Massachusetts, have invented certain new and useful Improvements in Eyeglass-Hooks, of which the following is a specification.

My invention relates to eyeglass hooks or 10 holders of the coiled spring type; that is, holders wherein the pin tongue spring is a coil adjacent or above the lip of the hook, in distinction from holders having uncoiled springs which are of little use because of 15 their frangibility.

The objects of my invention are essentially the provision of means for guiding the eyeglass spring or bridge into engagement with the hook, and in locating the spring coil in a 20 position which will not interfere with the attachment of the eyeglass to the holder, and will assist in preventing the forward tilting of the latter.

Other objects will be herein set forth. 25 To the above ends essentially my invention consists in the novel construction and combination of parts hereinafter set forth and claimed, and illustrated in the accompanying drawings, wherein

30 Figure 1 is a front elevation of my novel holder. Fig. 2, a side elevation of the same, showing in section a portion of the engaged garment; and, in broken lines, the pin-tongue in disengaged position, and Fig. 3, a rear elevation of the holder.

Like reference characters indicate like parts throughout the views.

The holder is formed from a single piece of wire and comprises the spring-loop, A, adjacent the convex portion of the usual flattened lip portion, B, of the hook, C. The wire continues downwardly from the spring loop forming a vertical bar, D, at whose lower end the material is bent laterally to form a horizontal loop, E, and continuing is bent to form a vertical loop, F, whose lower portion merges into the hook, C. Extending upwardly and rearwardly from the spring loop, A, the wire forms an inclined guide, G, which terminates in a higher plane than that of the top of the hook lip, B. The wire is then bent downwardly to form the pin tongue, H, whose point is adapted, when engaged, to rest against the inner edge of the loop, F, 55 whereby it is locked.

In Fig. 2, the pin is shown engaging the clothing, I.

The bridge of the eyeglass to be inserted into the holder contacts with the inclined guide, G, whereby the bridge is guided downwardly between the loop, A, and hook lip, B; and thus is avoided the usual trouble of the accidental insertion of the bridge behind the holder. The loops, E and F, prevent lateral rocking; and the vertical loop also serves as 65 a lock for the pin tongue.

It will be observed that the forward tilting of the holder is prevented by the natural contiguity of the spring loop, A, to the pin tongue, H, intermediate which elements the 70 fabric is pressed at a point considerably above the center of the holder, and in a location peculiarly adapted to prevent tilting of the device when an excessive or accidental strain is brought to bear upon its upper portion. 75

What I claim is,

1. In an eyeglass hook, the combination with the hook and a bar, of a spring coil upon the top of the bar adjacent the lip of the 80 hook, an inclined guiding portion extending upwardly from the spring coil and above the lip of the hook, and a pin tongue extending downwardly from the guiding portion.

2. In an eyeglass hook, the combination with the hook portion, the bar, and the pin tongue, of a spring coil upon the upper end of the bar and adjacent the hook and extended toward said tongue, and inclined means connecting the spring coil and tongue 90 and extending above the end of the hook for guiding an eyeglass into the hook. 85

3. In an eyeglass hook, the combination with the hook, bar, and catch device, of a spring coil adjacent the upper portion of the 95 hook, a vertical inclined portion above the spring coil and extended above the free end of the hook, and a pin tongue extending downwardly from the vertical portion adapted to coöperate with the spring coil to engage 100 an intermediate fabric.

In testimony whereof I have affixed my signature in presence of two witnesses.

STEPHEN J. CLULEE.

Witnesses:

HORATIO E. BELLows,
JOSEPH E. BURNS.
